PILE JUMP WEAVING

Frank W. E. Hoeselbarth, Carlisle, Pa., assignor to C. H. Masland & Sons, Carlisle, Pa., a corporation of Pennsylvania

Application March 31, 1954, Serial No. 420,088

20 Claims. (Cl. 139—39)

The present invention relates to pile fabrics especially of the character of carpets and rugs, and is applicable to velvet, tapestry, Wilton and Brussels weaving.

This application has been divided and the subject matter relating to the pile fabric is embodied in co-pending application Serial No. 493,256, filed March 9, 1955, now Patent No. 2,845,961, for Pile Jump Fabric.

A purpose of the invention is to provide in addition to the normal pile a jump pile which changes its lateral position either between two anchorages of a pile projection or at the point at which it is anchored in the backing of the weave, and forms a float or a diagonal pile projection.

A further purpose is to provide jump pile projections in addition to normal pile projections in the same transverse row of pile projections and to shift the lateral position of the jump pile projections at intervals along the fabric as a pattern may require, forming floats or diagonal pile projections.

A further purpose is to insert a jump pile warp in front of the reed and to move the jump pile warp heddle out of the way of the reed when the reed is beating up a weft or a weft and wire, and to move the jump pile warp laterally at intervals so that jump pile ends will appear in different courses.

A further purpose is to introduce the jump pile projections by a jump heddle moved downwardly from above adjacent to an open top reed.

A further purpose is to manipulate the jump pile warp by mechanism mounted on the reed, and moving vertically and also transversely.

A further purpose is to introduce the jump pile projections by a jump heddle moved downwardly adjacent to an open top reed.

A further purpose is to employ normal weaving of a normal pile and to superimpose on it a jump pile or a plurality of jump piles which are laterally manipulated as well as vertically manipulated in weaving.

A further purpose is to bind the jump pile behind back wefts while binding the normal pile behind front wefts.

A further purpose is to bind both the jump pile and the normal pile behind front wefts.

A further purpose is to employ a plurality of jump piles and to move them laterally at different positions, to different distances and desirably in some cases in opposition to one another, forming floats or diagonal pile.

A further purpose is to form high floats and low floats as desired by jump pile and where desired also to reject the jump pile in the back of the fabric.

A further purpose is to employ wires of any suitable character for raising the normal pile and the jump pile, including straight non-cutting wires, straight cutting wires, non-cutting wires having high and low portions along their lengths within the shed, cutting wires having high and low portions along their lengths within the shed and flag wires (having high portions beyond the shed) in any desired combinations alternating or interspersed

2

with one another, and with other wires where desired.

A further purpose is to provide an indexing shaft which is turned one way or another in accordance with a pattern control, and to shift the jump heddle laterally one way or another by mechanism interconnecting the indexing shaft and the jump heddle, suitably a rack and a pin and slot connection.

A further purpose is to provide two jump heddles and to feed yarn to both of them over a tension bar, adjusting the height of the jump heddle eyes so that the distance traversed by the yarn from the tension bar through the eyes of one jump heddle to the fell is the same as the distance traversed by the yarn from the tension bar through eyes of the other jump heddle to the fell.

Further purposes appear in the specification and in the claims.

In the drawings I have chosen to illustrate a few only of the numerous embodiments of my invention, selecting the forms shown from the standpoints of convenience in illustration, satisfactory operation and clear demonstration of the principles involved.

Figures 1 to 3 inclusive are conventional, longitudinal step-wise weave method diagrams showing the preferred embodiment of the invention.

Figure 4 is a warp-wise diagram of the completed weave of Figures 1 to 3 before removal of the wires.

Figures 5 to 7 inclusive are conventional, longitudinal step-wise weave method diagrams of a variant form of weaving in accordance with the invention.

Figure 8 is a warp-wise diagram of the completed weave of Figures 5 to 7 inclusive before removal of the wires.

Figures 9 to 11 inclusive are conventional, longitudinal step-wise weave method diagrams showing a further variant of the invention.

Figure 12 is a warp-wise diagram of the completed weave of Figures 9 to 11.

Figure 13 is a circuit diagram showing one form of mechanism for shifting the jump heddle laterally.

Figure 14 is a fragmentary diagrammatic view of one form of jump heddle drive.

Figures 15 and 16 are front elevations of different types of jacquard cards which may be employed in the invention.

Figures 17 to 21 are conventional longitudinal step-wise weave method diagrams showing a variant form of weaving in accordance with the invention.

Figure 22 is a warpwise diagram of the completed weave of Figures 17 to 21 before removal of the wires.

Figure 22a is a plan diagram showing the position of a jump pile warp end in Figure 22 in various courses and weft or wire positions.

Figure 23 is a variation in the weave of Figures 17 to 21, shown in a warpwise diagram of the completed weave before removal of the wires.

Figure 23a is a plan diagram of the face of a fabric in Figure 23, showing the position of the jump pile warp with respect to the wires and wefts.

Figures 24 to 28 are conventional stepwise weave method diagrams in the direction of the warp showing a further variation in the weave of the invention.

Figure 29 is a warpwise diagram of the completed weave of Figures 24 to 28 prior to removal of the wire.

Figure 29a is a plan diagram of the face of the fabric of Figure 29 showing a relation of a single jump warp end to the course and weft or wire positions.

Figure 30 is a weave plan diagram showing the jump from dent to dent.

Figure 31 is a view corresponding to Figure 30 showing variations.

Figures 32 to 35 are warpwise diagrams of completed weaves showing further variations.

Figures 32a, 33a, 34a and 35a are plan diagrams of the face of the fabric showing the relation of the single jump pile warp end to the course and weft or wire positions respectively in Figures 32, 33, 34 and 35.

Figures 36 to 40 are fragmentary diagrammatic elevations of the ends remote from the heads of wires according to the invention, showing at the right extreme ends of the wires beyond the shed and at the left a portion of each wire which is inside the shed.

Figure 41 is a diagrammatic warpwise section showing the feeding of yarn to a pair of jump heddles, and the manipulation vertically of the jump heddles.

Figure 41a is a diagram showing the components of the mechanism of Figures 41, 42 and 43.

Figure 42 is a diagrammatic transverse section showing an indexing shaft and its pattern control for manipulating the jump heddle laterally.

Figure 43 is a diagrammatic transverse section showing the interconnection between the indexing shaft and the jump heddle.

In the weaving of pile fabrics such as carpets and rugs on the velvet, tapestry, Wilton or Brussels systems, the pile warp ends are raised in the pile over wires, being bound behind wefts at the beginning and ending of each pile projection. The individual pile warp ends retain the same relation to other warp ends throughout the length of the fabric, and never leave the courses (lateral positions determined by dents of the reed) in which they are woven.

The present invention is designed to obtain novelty effects and enhance the appearance of the pattern, and also to permit more elaborate patterns without complication in the weaving. In accordance with the invention pile warp ends are employed which supplement the pile warps ordinarily used, or the weaving with the ordinary pile warps is modified, to permit the movement of float ends laterally so that they will be woven in different dents at different longitudinal positions. Thus these jump pile warps which move laterally can make the individual pile projection have anchorages at the two ends in different dents, or can move from one dent to another at a position at which the pile warp is bound behind a weft. In this way it is possible to make a particular group of jump pile warp ends appear successively as pile in different dents, and change by floating from dent to dent in successive pile rows.

In one form of the invention the jump pile warp is introduced in front of the reed, preferably by a jump heddle which moves down and up as required, moves out of the way when the reed must beat up a weft or a wire, and moves laterally to shift the position of the jump pile warp. The jump pile heddle may as desired be wholly independent of the reed, or may be mounted on the reed. In this form it is quite proper to use a reed which is closed at the top.

In another form, a jump pile warp heddle or heddles are used which are located between the normal heddles and the reed, and the top of the reed is open. At a position in the weaving between any two steps, the jump pile warp heddle or heddles are raised above the reed and moved laterally and then lowered to insert the ends in different dents. The yarn is fed in downwardly to the jump pile heddles in front of the other heddles.

In accordance with the invention the jump pile warp can be anchored in the weave behind back wefts or face wefts, and can appear in the pile in every transverse row, alternate transverse rows or widely spaced transverse rows.

Where a plurality of jump pile heddles are used, the lateral movement of the jump pile warps may take place at different times, to different distances, and desirably with opposite movements.

The jump pile warps may also appear in high and in low floats, and the jump pile warp or warps can also be rejected as desired.

Where desired the jump pile warps can form the entire pile instead of merely making an auxiliary pile.

The jump pile warp can be controlled in its lateral

movement by a jacquard mechanism, or any other suitable pattern control. One mechanism suitable for manipulating the jump pile heddle is an indexing shaft controlled by a dobby chain.

5 The heights of the eyes on a plurality of jump heddles are preferably adjusted so that the same yarn take-off can be used for the pile yarn for both jump heddles.

The invention is applicable to velvet, tapestry, Wilton and Brussels carpet weaving, and in any desired row the pile may be cut, uncut, uniform in height, high and low, or of several different heights as desired.

In order to illustrate the invention, I show primarily velvet carpet weaves, although it will be understood that the pile warp ends either of the normal pile or of the jump pile or both will where desired be selectively raised by a pattern control such as a jacquard.

Jump pile warps forming floats are not to be confused with lappet warps, which move laterally underneath the backing of the fabric and rise through the backing at intervals to form tufts on the face of the fabric. Strong, Fabric Structure (Chemical Publishing Co., 1947) 200 to 203.

In the form of Figures 1 to 3 inclusive, illustrated as a completed weave in Figure 4, the jump pile warp is introduced in front of the reed (between the reed and the fell), and is employed along with a normal pile warp, and in association with two binder warps and a stuffer warp. Normal pile warp 60 withdrawn from a suitable source and tensioned by a suitable tensioning device, manipulated by a pile warp heddle 63, extends to a fell 64 through a reed 65 which is desirably of the conventional type, having a closed top. Binder warp 66 withdrawn from a suitable source through a suitable tensioning device is manipulated by binder warp heddle 70 and extends throughout the reed to the fell. Binder warp 71 also withdrawn from a suitable source through a suitable tensioning device is manipulated by binder warp heddle 72 and likewise passes through the reed to the fell. Stuffer warp 73 is withdrawn from a suitable source through a suitable tensioning device, is manipulated by stuffer warp heddle 76 and passes through the reed to the fell.

Positioned in front of the reed in the retracted position of the reed is jump pile warp 77, which is manipulated up and down and laterally as later explained by jump pile warp heddle 78. The jump pile warp heddle consists of individual suitably metallic wires or strips extending down individually without any cross connection at the bottom and the wires have eyes at the bottom as shown, so that when the jump heddle is lowered at any lateral position it can move down among other warp ends, and when raised it can shift laterally above the other warp ends and when lowered again it can move down among the other warp ends. It will be understood, of course, that the jump heddle may have ends in each course or if desired may only have ends in certain courses, omitting ends in other courses.

In the first step of the weave as shown in Figure 1, with the reed 65 retracted, a lower shed 80 is formed by adjusting the heddles to raise binder warp 66 halfway and lower normal pile warp 60, jump pile warp 77, binder warp 71 and stuffer warp 73 as shown. A shot of weft 81 is inserted in the lower shed.

In the next step as shown in Figure 2, the jump pile warp heddle 78 is raised, so that the lower end of the jump pile warp heddle is above the top of the reed, and the jump pile warp passes under the weft 81 and then up in front of the reed. In the position of Figure 2, the reed then moves toward the fell to beat up the weft as in normal practice, the tensioning device applied to the jump pile warp tending to hold the jump pile warp ends reasonably taut as the weft is beaten up.

According to the pattern demand as later described, the jump pile heddle moves laterally at a suitable step in the weave and this may be immediately after the step of Figure 2 and before the step of Figure 3, or it may be

after the step of Figure 3 and before the next step of Figure 1.

Between Figure 2 and Figure 3 the jump pile warp heddle desirably remains raised and a new shed is formed as shown in Figure 3. In this position the heddles are adjusted so that normal pile warp 60 is fully raised, and stuffer warp 73 and binder warp 66 are raised halfway, forming an upper shed 82. Binder warp 71 is lowered forming a lower shed 80. Jump pile warp 77 is fully raised. Wire 83 is inserted in the upper shed and a weft 84 is inserted in the lower shed. The reed then proceeds immediately to beat up the weft and the wire, since the jump pile warp heddle is raised out of the way.

Between the step of Figure 3 and the step of Figure 1 on the next cycle the binder warps reverse.

The completed weave as shown in Figure 4 illustrates normal pile projections 85 and jump pile projections at 86 which are bound behind adjoining front wefts. It will be understood, however, that the jump pile projections, at least in some instances, move laterally from one course to another between the point of bind behind one weft and the point of bind behind the next weft. It will also be evident that the jump pile projections as also the normal pile projections need not in every case be present in every course.

Whereas in Figures 1 to 4 the fabric includes jump pile and normal pile warp ends, the invention can be applied to weave a pile fabric with only jump pile warp ends as shown in Figures 5 to 8. Also whereas in the form of Figures 1 to 4, the jump pile heddle is independent of the reed, the jump pile heddle can be supported on the reed as shown in Figures 5 to 7.

Figure 5 shows a weave position in which the heddles are adjusted to place the jump pile warp 77 down, binder warp 66 raised halfway, binder warp 71 lowered, and stuffer warp 73 lowered. A slide 87 is mounted on the top of the reed and slides laterally thereon and the jump pile warp heddle 78' moves up and down in the slide. A shot of weft 81 is taken in the lower shed 80.

In the next step as shown in Figure 6, the jump pile warp heddle 78' has moved up in the slide to a position above fell 64. The reed 65 is then in position to beat up the weft without striking the jump pile warp heddle against the fell.

Between the positions of Figures 6 and 7, the slide 87 will move laterally as the pattern requires to place the jump pile warp ends in a different course. The jump pile warp heddle 78' is fully raised defining an upper shed 82, while binder warp 66 and stuffer warp 73 are raised halfway and binder warp 71 is fully lowered forming a lower shed. A wire 83 is inserted in the upper shed and a shot of weft 84 is inserted in the lower shed. Between the step of Figure 7 and the next step of Figure 5 which completes the cycle the binder warps are reversed, but the procedure is otherwise the same as in the Figure 5.

In the finished fabric as shown in Figure 8, the only pile projections are jump pile projections 86 but they are in different courses at different weft positions as the pattern requires.

In some cases it is desirable to put in more than two jump pile warps in front of the reed and this is shown in Figures 9-11. Figure 9 is like Figure 5 except that the jump pile warp heddles 78 and 78' are separated from and not supported on the reed, and two jump pile warps 77 and 77' are inserted in front of the reed. Otherwise, Figure 9 is like Figure 5, Figure 10 is like Figure 6 and Figure 11 is like Figure 7. Between the position of Figures 10 and 11 the jump pile warps move laterally as the pattern requires, and it will be understood that the different jump pile warps do not usually move in the same way, the respective movements being two different distances in the same direction or oppositely as desired.

Thus, in Figure 12 there are jump pile projections

86 and 86' each of which suitably originates and ends in a different course, and the jump pile projections 86 move laterally in different directions or different distances from the jump pile projections 86'.

5 Any one of a variety of different mechanisms may be employed to move the jump pile warp heddles laterally, the form of Figures 13 to 16 showing a jacquard mechanism suitable for this purpose. Figure 14 illustrates a slide 87 which is the slide connected to the jump pile warp heddle, which slide provides a support to permit the jump pile heddle to move vertically under heddle action as well as to move horizontally. The slide 87 carries at one end a screw 88 which is in threaded relation to a nut 90 supported against lateral motion by bearings 91 which permit the nut to turn. The bearings are on a fixed support and do not thread with the screw. A reversible motor 92 having right and left hand drive-windings 93 and 94 carries on its motor shaft a worm 95 which intermeshes with worm wheel teeth 96 on the outside of nut 90.

10 Jacquard cards 97 and 97' have two sets of control positions 98 and 100, which have holes 101 clearing from jacquard needles 102 of well-known character at positions at which selection is not to be made and have a blank 103 engaging the needle where selection is to be accomplished. When the card is pushed in against the needles, the needles opposite the holes 101 are unaffected, but the needle opposite the blank 103 is displaced. Each of the needles in the set 98 engages and by displacement closes a normally open switch 104 which controls motion of the slide 87 in one direction and each of the needles in the set 100 engages and by displacement closes one of the normally open switches 105 which controls motion of the slide 87 in the opposite direction.

15 20 25 30 35 40 45 50 Each of the switches 104 and 105 connected to one side of the source is in series with an impedance 106 in one of the several parallel branches connected from the power source to the particular motor winding 93 or 94 and each impedance 106 is shunted by the magnet coil of a limit switch relay 107. The other side of the windings 93 and 94 are connected together at 108 and connected to the other side of the source. Each limit switch relay by energization deflects a limit switch armature 109 pivotally connected at 109' to a limit switch dog 110 on a fixed pivot 110' against the action of tension spring 111 into the path of the operator of a normally closed switch 112 which is the circuit branch 108. The limit switch relays are placed at appropriate positions so as to stop action of the motor as soon as the limit switch is tripped and to hold the switch 112 open as long as the relay is energized.

55 60 65 70 75 In operation of the device of Figures 13 to 16, as soon, for example, as the jacquard cylinder turns and indexes the card 97 against the needles, the blank 103 of the operator set 98 closes one of the switches 104 which energizes the motor winding 94 in one direction of rotation, and energizes one of the limit switch relays 107 to move its armature dog 110 out into the path of the slide. The motor moves the slide in the direction required and when the slide moves the predetermined distance switch 112 which is normally closed is opened and held opened by the relay armature 110 just described, stopping the operation of the motor 92. The motor remains inoperative until the jacquard cylinder retracts and indexes the next card 97' and moves in to engage the needles. Blank 103' then closes one of the switches 105 energizing the motor winding 93 to move the motor in the reverse direction until stopped by the corresponding limit switch armature dog 110 energized by the relay winding. The operation stops when switch 112 is opened by the limit armature, and the motor is not again energized until the next jacquard card is indexed.

In the description thus far given, the jump pile warp ends have been put in front of the reed, but it will be

understood that they can be put in behind the reed providing an open-top reed is used.

In Figure 17 I illustrate one normal pile warp 60 manipulated by a heddle 63, withdrawn from a source such as beam 61 and tensioned by a device 62. A second normal pile warp 60' is manipulated by heddle 63' and is drawn from a suitable source such as beam 61' through tensioning device 62'.

A jump pile warp 77 withdrawn from a suitable source and through a suitable tensioning device, not shown, is fed directly downwardly behind the reed to a jump pile warp heddle 78³ having eyes at the bottom but no lower portion or lower cross connection.

Stuffer warp 73 manipulated by stuffer warp heddle 76 is withdrawn from a suitable source such as beam 74 through tensioning device 75.

It is immaterial from the standpoint of the present invention whether a single binder warp or a pair of binder warps is used and for convenience I have shown a pair of binder warps. Binder warp 71 manipulated by binder warp heddle 72 is withdrawn from a suitable source such as beam 67 through tensioning device 68. Binder warp 66 manipulated by binder warp heddle 70 is withdrawn from the same beam through the same tensioning device.

Reed 65², unlike the usual reed employed in this art, has no top, so that it is possible to shift the jump pile warp ends from dent to dent by raising the jump pile warp heddle above the reed, making the shift, and lowering the jump heddle to bring the jump pile warp ends into different dents.

In Figure 17, jump pile warp heddle 78³ is fully raised, although still below the top of the reed, and normal pile warp 60 is also fully raised, binder warp 71 is raised half way, forming an upper shed, and all other warps, that is, rejected pile warp 60', stuffer warp 73 and binder warp 66 are lowered, forming a lower shed. Wire 83 is inserted in the upper shed and a shot of weft 84 is inserted in the lower shed. By reference to Figure 22, it is seen that the shot of weft 84 is here a face weft since it is in front of the stuffer warp. The reed beats up the weft and the wire, concluding the first step.

If desired the lateral shifting of the jump pile warp can take place between the first and the second step by raising the jump pile warp heddle above the reed, moving it laterally and reinserting it in the reed at a different position. It is preferred, however, to employ this feature at a later stage in the cycle as later explained.

In the second step as indicated in Figure 18, binder warp 66 is fully lowered, and in this particular weave jump pile warp 77 is also fully lowered, and all other warps are raised half-way, forming the lower shed. A shot of weft 81 is inserted in the lower shed in this instance forming a back weft as shown in Figure 22.

Immediately after the step of Figure 18 in the preferred embodiment, the jump pile warp heddle 78³ is raised above the top of the reed as shown in Figure 19 (above the normal fully raised position), moved laterally and reinserted into the reed. The number of dents of lateral movement will preferably not exceed 4 at any one time, and in many cases a movement of one or two dents laterally at any one time will be entirely satisfactory. In some cases a lateral movement of more than four dents will be used. This movement laterally takes place before the jump pile warp is raised over the next wire in this form (and thus is buried in the back of the fabric) and will not show by angular position of the pile projections as it would in case this was accomplished after the jump pile warp had been raised over the wire but before it was anchored behind the following weft.

In the next step as indicated by Figure 20, normal pile warp 60' is fully raised and jump pile warp 77 is fully raised but still low enough so that the jump pile warp ends are in the reed. Binder warp 66 is raised half-way and all other warps are lowered, forming a lower and an upper shed respectively. A wire 83 is inserted in the

upper shed and a shot of face weft 84 is inserted in the lower shed.

In the next step as shown in Figure 21, binder warp 71 is lowered, jump pile warp 77 is also lowered, and all other warps are raised, forming a lower shed into which back weft 81 is inserted as in Figure 18.

If desired the jump pile warp may be raised above the top of the open reed, moved laterally and reinserted in the reed at a different lateral position between the steps of Figures 20 and 21, in which case there will be a tendency to produce a diagonal pile projection of the jump pile warp, or it may be raised, moved laterally and reinserted between the step of Figure 21 and the step of Figure 17 of the next cycle, in which case the lateral movement will be buried in the back of the fabric, but the jump pile warp will appear in a different course or dent position. Thus the final result as shown in Figure 22 is to produce alternate rows of normal pile projections 85 in one transverse row and of normal pile projections 85' in the next transverse row, with the jump pile warp ends woven behind back weft 81 and appearing over the wire in each row. However, a particular jump pile warp end will appear for example in course A in the first row, course B of the second row, course C of the third row and course D of the fourth row of Figure 22, the lateral movement being determined in direction and extent by the pattern.

While in Figures 17 to 22 the jump pile projections appear in each transverse row, they may instead appear in alternate transverse rows and be bound behind front wefts instead of back wefts as shown in Figure 23. In this form there are jump pile projections 86 raised with pile projections 85' in alternate transverse pile rows, but the particular jump pile warp end shown in Figures 23 and 23a appears successively in courses A, B and C, as shown. It will be understood that with the thread-in used the jump pile warp ends need not appear in every dent, or course and if desired they may employ multiple ends in a particular dent or in certain dents. Likewise the thread-in of the normal pile warp ends or of the jump pile warp ends or both may include the use of ends of successively different colors as the pattern dictates so that variations in pattern effects can be obtained by leaving pile warp ends out of particular dents, placing multiple pile warp ends in certain dents and fewer or no ends in other dents, and changing the color or material of the ends between different dents.

The invention is also applicable to weaves in which there are a plurality of jump pile warps operated by a plurality of jump pile warp heddles introduced behind an open reed as shown in Figures 24 to 28 inclusive, which except for the use of multiple jump pile warps follow the steps of Figures 17 to 21. It will be understood that the jump pile warps 77 and 77' and the heddles 78³ and 78⁴ can be woven together as shown in Figures 24 to 28, but with different lateral positions, or can be woven oppositely or differently as later explained.

Figure 29 shows the result of raising the jump pile warps with alternate normal pile warps, shifting the jump warp ends into different dents as indicated by the letters A and B at different transverse rows to indicate the dents occupied by jump warp end 77.

The lateral manipulation will vary widely with the pattern, Figure 30 showing dents or courses 113 to 116 and face wefts 84, 84', 84², etc. The normal pile warp ends, binder warp ends, and stuffer warp ends are omitted. Thus the jump pile warp end of warp 77 which is shown in Figure 30 is in dent 113 between the wefts 84 and 84', moves to dent 114 between wefts 84' and 84², remains in dent 114 until in a position between weft 84³ and 84⁴, then moves to dent 115. On the other hand the particular end of jump pile warp 77' shown remains in dent 113 until, in the position between weft 84³ and 84⁴, it jumps laterally to dent 116 where it remains for several cycles.

Other ends of each jump pile warp behave similarly. As already explained it is a matter of pattern and weave design whether the jump is to take place before the particular jump pile warp is raised in the pile or after it has been raised over the wire and before it is anchored behind the next dent, the difference being primarily that the pile projection will be diagonal in the latter case and not in the former case. The jump pile warp end in the particular dent will normally be threaded-in beside the normal pile warp end.

In some cases it will be desirable to manipulate the jump heddles in opposition laterally as shown in Figure 31. Here the jump pile warp 77 of which one end is shown, is in dent 113 and moves to dent 114 between face weft positions 84 and 84', and remains there until between face weft position 84³ and 84⁴ it moves back to dent 113. Likewise the jump pile warp 77' of which one end is shown, is in dent 114 and moves to dent 113 between face wefts 84 and 84', and then moves to dent 114 between face wefts 84³ and 84⁴. Other ends of each jump pile warp behave similarly.

The invention is applicable to high and low floats. In Figures 32 and 32a at least some of the ends of jump pile warp 77 form high floats 117 over two wires, being bound behind face wefts on either side, while at least some of the ends of jump pile warp 77' in succeeding rows form high floats 118 over two wires, bound behind face wefts at the sides. As indicated by the letters A and B, the particular end of jump pile warp 77' shown is in dent B over the left hand wire, and in dent A over the third and fourth wires, while the particular end of jump pile warp 77 shown is in dent A over the second and third wires and will be in dent B over the fifth wire (not shown), counting from the left in each case.

The invention is equally applicable to low floats, in which the float passes over one wire and between the face weft and the next wire as in Figures 33 and 33a. In this form only one jump pile warp is shown which is at dent A where it rides over the wire and at dent B where it travels between the wire and the face weft.

In some cases the jump pile warp will be wholly rejected and this is shown at 120 in Figures 34 and 34a. Unlike the usual rejected warp, however, the jump pile warp ends shown travel from dent A to dent B in weaving from left to right. It will, of course, be understood that it can move considerable distances laterally in the back of the fabric where it is rejected at 120 moving in jumps of 1, 2 or 3 or more dents preferably at a given weft position.

Where desired all of the pile warps may be jump pile warps where the jump pile warp is introduced behind an open reed as shown in Figures 35 and 35a. This corresponds in general to Figure 23, omitting any separate normal pile warp and raising the piles alternately in alternate face weft positions over wires. Unlike the usual weaving procedures, however, the end shown of jump pile warp 77 is in dent A at the fifth wire, while the end shown of jump pile warp 77' is in dent A at the second wire and in dent B at the fourth wire. Thus in effect the jump pile warps move laterally through some predetermined pattern sequence which may be a criss-cross, a zigzag, an oval, a diamond or the like, and are capable of creating novel effects without a jacquard raising the pile ends or supplementing a jacquard, especially where different ends of a particular pile are of different colors at different lateral positions across the pile warp.

No attempt has been made in the present invention to illustrate all the possible wire combinations and embodiments which will be employed in particular cases, it being sufficient merely to indicate different types of wires which will be used either uniformly or in various combinations or sequences. Figure 36 illustrates a straight non-cutting wire 83', Figure 37 illustrates a straight cutting wire 83², Figure 38 illustrates the non-cutting wavy wire 83³ having high and low portions along its top within the shed, Figure

39 illustrates a cutting wavy wire 83⁴ having high and low portions along its top within the shed and a cutter beyond the shed and Figure 40 illustrates a flag wire 83⁵ which is permissibly straight within the shed but has a high flag portion beyond the shed. The form of flag wire shown is non-cutting though it will be understood that cutting flag wires can also be used.

Figure 41 illustrates mechanism which may desirably be employed for raising and lowering the jump heddles under suitable cam control and for feeding jump pile yarn to the jump heddles. In this case two jump heddles 78³ and 78⁴ are supported in laterally sliding bearings on the lower ends of slide 87' which are pivotally connected at the sides of the loom beyond the shed to tension rods 121.

15 The tension rods 121 at the two sides beyond the shed are supported on arms 122 pivoted at 123 and swingable to raise and lower the jump heddles as required. Thus at one part of the loom motion the jump heddles are located so that their yarn ends are below the top of the open top reed 65² (or below and in front of the reed if that form is used), while at another time when the jump heddles are individually to be moved laterally they are raised as shown in Figure 41 so that their yarn ends are wholly above the top of the open top reed 65².

20 25 Jump pile yarn 77 and 77' are received from any usual let-off under any suitable tensioning mechanism. The yarn may desirably be withdrawn from the same warp beam. The feed of the yarn passes around the lower edge of pivot bar 123 and over the top of tension bar 121 laterally inside the shed, and jump pile yarn ends 77 to pass through the eyes of the jump heddle 78³ are carried relatively forward of jump pile yarn ends 77', which, to pass through the eyes of jump heddle 78⁴, are carried backward as they move down. The jump pile heddle wire or 30 35 needle of jump pile heddle 78⁴ is made slightly longer than the corresponding wire or needle of jump pile heddle 78³ (suitably about 1/4 inch longer), so that the distance from the tension bar 121 through the eye to the fell is the same in both cases and the vertical movement of the 40 45 jump pile heddles compensates for the yarn tension and keeps it the same on both jump pile warps, as the tension bar swings.

The normal pile warp, stuffer and binder warp are manipulated by the usual heddles.

45 The lateral movement of the jump pile warp or warps may be controlled by a dobby chain pattern mechanism of which Figures 42 and 43 show one example, for controlling a single jump pile heddle. This mechanism would be duplicated for additional jump pile heddles, suitably 50 using a tubular indexing shaft and placing another indexing shaft within it.

55 Indexing shaft 124 mounted on suitable bearings and extending parallel to the warp direction has an indexing gear 125 mounted thereon. An escapement yoke 126 bridges the gear 125 and has opposed indexing hooks 127 and 128. At each step in weaving at which the jump heddle is to move laterally, pull rod 130 on which the escapement yoke 126 is pivoted at 131 moves up so that the hooks move past the gear 125 and one or the other 60 hook 127 or 128 engages one or the other side of the escapement gear and moves the escapement gear clockwise or counterclockwise as the case may be for one tooth. The pull rod 130 then moves down without shifting the escapement shaft 124 because spring detent 132 mounted 65 in sliding bearing 133 is urged by helical compression spring 134 acting against spring abutment 135 on the detent into one of the notches of detent gear 136 on the same shaft 124 and the hooks slip pass the teeth of the index gear 125 without changing position.

70 The position of the indexing hooks 127 and 128 is adjusted by pattern links 137 on a pattern chain 138 fed in the usual way, one link at a time, from a chain case 140 over a guide 141 to a pattern link sprocket 142 advancing 75 on shaft 143 so that the links engage follower arm 144

from the escapement yoke which is urged against the controlling link by helical compression spring 145.

The pattern link chain has three kinds of pattern links which are determined by the designer. A low link allows the escapement yoke to move toward the left and would move the jump heddle to the right as later explained. A medium high pattern link causes no movement of the indexing shaft and thus retains the previous setting. A high pattern link will cause a reverse movement to that previously described. The pattern chain sprocket is advanced step by step as by a hook as well known in the art, and is held in its last position until further advances as well known in the art.

The connection between the indexing shaft 124 and the jump heddle can take any one of a wide variety of forms. In Figure 43 the jump heddle 78³ has at its end a pin 146 which extends warpwise and rides in a vertical slot 147 on a rack 148 which reciprocates in guide bearings not shown. A pinion 150 on the indexing shaft 124 engages the rack.

The invention finds its widest application in carpets and rugs at the present time but it will be understood that it is also applicable to other fabrics such as upholstery fabrics and the like.

In view of my invention and disclosure variations and modifications to meet individual whim or particular need will doubtless become evident to others skilled in the art, to obtain all or part of the benefits of my invention without copying the process, apparatus and fabric shown, and I, therefore, claim all such insofar as they fall within the reasonable spirit and scope of my claims.

Having thus described my invention what I claim as new and desire to secure by Letters Patent is:

1. The process of weaving a pile fabric using a reed and heddles, which comprises interweaving together a jump pile warp, at least one binder warp, and wefts, while inserting the jump pile warp at a position between the heddles for other warps and the fell, raising the jump pile warp over transverse pile wires and binding it behind wefts at intervals, and moving the jump pile warp laterally for a distance of more than one dent and inserting the ends in different spaced dents at different positions along the weaving.

2. The process of weaving a pile fabric, using a reed and heddles, which comprises interweaving together a plurality of jump pile warps, at least one binder warp, and wefts, while inserting the jump pile warps between the heddles for the other warps and the fell, raising the jump pile warps over transverse pile wires and binding them behind wefts at intervals, and in accordance with a pattern shifting the respective jump pile warps laterally by a distance of more than one dent to insert their ends in different courses.

3. The process of weaving a pile fabric, using a reed and heddles, which comprises interweaving together at least one jump pile warp, at least one normal pile warp, at least one binder warp, at least one stuffer warp, and wefts, the jump pile warp being inserted between the heddles for the other warps and the fell, raising the normal pile warp over transverse pile wires to form normal pile projections which continue in the same course, raising the jump pile warp over transverse pile wires to form pile projections, and at intervals in the weaving moving the jump pile warp ends laterally from one course to another.

4. The process of weaving a pile fabric using a reed, which comprises interweaving together at least one jump pile warp, at least one binder warp, and wefts, while inserting the jump pile warp in front of the reed, raising the jump pile warp over transverse pile wires to form pile projections at the face of the fabric and binding it behind wefts spaced by at least two intermediate binding wefts, and at intervals moving the jump pile warp laterally to place its ends in different courses.

5. The process of weaving a pile fabric using a reed, which comprises interweaving together at least one jump

pile warp, at least one binder warp, at least one stuffer warp, and wefts, inserting the jump pile warp between the reed and the fell, moving the jump pile warp upward to a position at which it will not interfere with the reed contacting the fell to beat up, raising the jump pile warp over transverse pile wires to form pile projections at the face of the fabric and at intervals moving the jump pile warp laterally when it is above other warps to place its ends in different courses spaced by at least one intermediate course.

6. The process of weaving a pile fabric using a reed, which comprises interweaving together a plurality of jump pile warps, at least one binder warp, and wefts, while inserting the jump pile warp between the reed and the fell, raising the jump pile warps to a position out of the way of the reed contacting the fell to beat up, raising the jump pile warps over transverse pile wires to form pile projections, and at intervals moving the respective jump pile warps to different courses under pattern control while the jump pile warps are raised above other warps to insert the jump pile warp ends in different courses.

7. The process of weaving a pile fabric using a reed having an open top, which comprises interweaving together at least one normal pile warp, at least one jump pile warp, at least one binder warp, and wefts, raising the normal pile warp successively over transverse pile wires to form pile projections at the face of the fabric, raising the jump pile warp successively over transverse pile wires to form pile projections at the face of the fabric, and at intervals raising the jump pile warp above the reed, moving it laterally and reinserting it in the reed at a different dent.

8. The method of weaving a pile fabric, using a reed having an open top, which comprises as a first step raising at least one normal pile warp and at least one jump pile warp into an upper position, placing another warp in an intermediate position, thus forming an upper shed, placing at least one other pile warp in a lower position, thus forming a lower shed, inserting a transverse pile wire in the upper shed, inserting a weft in the lower shed, as a second step forming a lower shed of the warps and inserting a weft, as a third step fully raising at least one pile warp and the jump pile warp, raising another warp half way, thus forming an upper shed, lowering at least one other pile warp and thus forming a lower shed, inserting a transverse pile wire in the upper shed, inserting a weft in the lower shed, and as a fourth step raising some warps half way, lowering other warps, thus forming a lower shed, inserting a weft in the lower shed, thereby binding pile warps raised over wires behind wefts, and between one of these steps and the next step lifting the jump pile warp above the reed, shifting it laterally and reinserting it in the reed at a different lateral position.

9. The method of weaving a pile fabric, using a reed having an open top, which comprises as a first step raising at least one normal pile warp and at least one jump pile warp into an upper position, placing another warp in an intermediate position, thus forming an upper shed, placing at least one other pile warp in a lower position, thus forming a lower shed, inserting a transverse pile wire in the upper shed, inserting a weft in the lower shed, as a second step forming a lower shed of the warps and inserting a weft, as a third step fully raising at least one pile warp and the jump pile warp, raising another warp half way, thus forming an upper shed, lowering at least one other pile warp and thus forming a lower shed, inserting a transverse pile wire in the upper shed, inserting a weft in the lower shed, and as a fourth step raising some warps half way, lowering other warps, thus forming a lower shed, inserting a weft in the lower shed, thereby binding pile warps raised over wires behind wefts, and between the first step and the second step lifting the jump pile warp above the reed, shifting it laterally and reinserting it at a different position in the reed.

10. The method of weaving a pile fabric, using a reed

13

having an open top, which comprises as a first step raising at least one normal pile warp and at least one jump pile warp into an upper position, placing another warp in an intermediate position, thus forming an upper shed, placing at least one other pile warp in a lower position, thus forming a lower shed, inserting a transverse pile wire in the upper shed, inserting a weft in the lower shed, as a second step forming a lower shed of the warps and inserting a weft, as a third step fully raising at least one pile warp and the jump pile warp, raising another warp half way, thus forming an upper shed, lowering at least one other pile warp and thus forming a lower shed, inserting a transverse pile wire in the upper shed, inserting a weft in the lower shed, and as a fourth step raising some warps half way, lowering other warps, thus forming a lower shed, inserting a weft in the lower shed, thereby binding pile warps raised over wires behind wefts, and between the second step and the third step lifting the jump pile warp above the reed, shifting it laterally and reinserting it at a different position in the reed.

11. The method of weaving a pile fabric, using a reed having an open top, which comprises as a first step raising at least one normal pile warp and at least one jump pile warp into an upper position, placing another warp in an intermediate position, thus forming an upper shed, placing at least one other pile warp in a lower position, thus forming a lower shed, inserting a transverse pile wire in the upper shed, inserting a weft in the lower shed, as a second step forming a lower shed of the warps and inserting a weft, as a third step fully raising at least one pile warp and the jump pile warp, raising another warp half way, thus forming an upper shed, lowering at least one other pile warp and thus forming a lower shed, inserting a transverse pile wire in the upper shed, inserting a weft in the lower shed, and as a fourth step raising some warps half way, lowering other warps, thus forming a lower shed, inserting a weft in the lower shed, thereby binding pile warps raised over wires behind wefts, and between the third step and the fourth step lifting the jump pile warp above the reed, shifting it laterally and re-inserting it at a different position in the reed.

12. The method of weaving a pile fabric, using a reed having an open top, which comprises as a first step raising at least one normal pile warp and at least one jump pile warp into an upper position, placing another warp in an intermediate position, thus forming an upper shed, placing at least one other pile warp in a lower position, thus forming a lower shed, inserting a transverse pile wire in the upper shed, inserting a weft in the lower shed, as a second step forming a lower shed of the warps and inserting a weft, as a third step fully raising at least one pile warp and the jump pile warp, raising another warp half way, thus forming an upper shed, lowering at least one other pile warp and thus forming a lower shed, inserting a transverse pile wire in the upper shed, inserting a weft in the lower shed, and as a fourth step raising some warps half way, lowering other warps, thus forming a lower shed, inserting a weft in the lower shed, thereby binding pile warps raised over wires behind wefts, and between the fourth step and the first step of the next cycle lifting the jump pile warp above the reed, shifting it laterally and reinserting it in the reed at a different reed position.

13. The method of weaving a pile fabric with a reed having an open top, using at least one normal pile warp, at least one jump pile warp, at least one binder warp, at least one stuffer warp and wefts, which comprises successively raising the normal pile warp over transverse pile wires, inserting face wefts and inserting back wefts, feeding in the jump pile warp immediately adjoining the reed from above, at intervals raising the jump pile warp over transverse pile wires and binding it behind wefts and at successive weaving positions along the length of the fabric raising the jump pile warp above the open top of

14

the reed, shifting it laterally and reinserting it into the reed at a different dent position.

14. The method of weaving, using a reed having an open top, which comprises in the first step fully raising a jump pile warp and feeding in the jump pile warp from above immediately adjoining the reed, fully raising another pile warp, raising a binder warp half way and lowering other warps, thus forming an upper shed and a lower shed, inserting a transverse pile wire in the upper shed, inserting a weft in the lower shed, in the second step lowering the jump pile warp and at least one binder warp, raising the other warps half way and thus forming a lower shed and inserting a shot of weft in the lower shed, in the third step fully raising the jump pile warp and feeding in the yarn from above immediately adjoining the reed, fully raising another pile warp, raising another binder warp half way, lowering all other warps, thus forming an upper shed and a lower shed, inserting a transverse pile wire in the upper shed, inserting a shot of weft in the lower shed, in the fourth step lowering the binder warp last mentioned, lowering the jump pile warp, raising all other warps half way and inserting a shot of weft, repeating the weaving cycle and at intervals between steps raising the jump pile warp above the top of the reed, moving it laterally and reinserting it at a different position in the reed.

15. The method of weaving a pile fabric, using an open top reed which comprises in the first step fully raising one normal pile warp, raising a binder warp half way, lowering all other warps including a jump pile warp, thus forming an upper shed and a lower shed, inserting a transverse pile wire in the upper shed, inserting a shot of weft in the lower shed, in the next step lowering another binder warp and raising all other warps half way, thus forming a lower shed, inserting a shot of weft in the lower shed, in the next step fully raising another normal pile warp, fully raising a jump pile warp and feeding in the jump pile warp immediately adjoining the reed, raising the other binder warp half way and lowering all other warps, thus forming an upper shed and a lower shed, inserting a transverse pile wire in the upper shed and inserting a shot of weft in the lower shed, in the next step lowering the one binder warp and raising all other warps half way and inserting a shot of weft in the lower shed thus formed, and repeating the cycle, raising the jump pile warp above the top of the open reed, moving it laterally and reinserting it in a different position in the reed between two of the steps.

16. The method of weaving a pile fabric, which comprises interweaving at least one normal pile warp, at least one jump pile warp, at least one binder warp, at least one stuffer warp and wefts, at intervals along the length of the fabric raising the normal pile warp in pile projections over transverse pile wires, at intervals along the length of the fabric raising at least some of the ends of the jump pile warp over at least two adjoining transverse pile wires and at intervals along the length of the fabric shifting the lateral position of the jump pile warp in weaving.

17. The method of weaving a pile fabric, which comprises interweaving at least one normal pile warp, at least one jump pile warp, at least one binder warp, at least one stuffer warp and wefts, at intervals along the length of the fabric raising the normal pile warp over transverse pile wires in pile projections, at intervals along the length of the fabric raising the jump pile warp over one transverse pile wire and carrying it beneath the adjoining transverse pile wire but over the adjoining face weft, and shifting the lateral position of the jump pile warp in weaving.

18. The method of weaving a pile fabric, which comprises interweaving together a plurality of normal pile warps a plurality of jump pile warps, at least one binder warp, at least one stuffer warp and wefts, raising the normal pile warps over transverse pile wires at suc-

sive face weft positions, raising the successive jump pile warps each over a pair of adjoining transverse pile wires at different longitudinal positions and shifting the lateral positions of the jump pile warps in weaving.

19. In a loom, a reed movable to beat up, heddles on the side of the reed remote from the fell, a slide supported on the upper part of the reed and movable laterally from one dent position to another back and forth across the loom, a jump pile warp heddle supported on the slide on the side of the reed toward the fell and movable vertically and a set of transverse pile wires for insertion in the weave. 5

20. In a loom, a reed movable toward and away from the fell, heddles vertically movable on the side of the reed remote from the fell, a jump pile warp heddle between the heddles and the fell, movable vertically and having a slide movable laterally for more than one dent, a jacquard mechanism having cards, needles engaged by the cards, jacquard switches in the jacquard mechanism, one of which is selectively closed by one of the needles, a reversible motor connected with the slide and having a clockwise driving winding and a counter-clockwise driving winding, and electric circuit means including parallel circuits for the jacquard switches, connected re- 15 20

spectively to one or the other of the motor windings and including limit switch means controlled by the jacquard switch to stop the operation of the motor in a particular direction.
